United States Patent Office.

H. A. KEPHART, OF FLETCHER, OHIO.

Letters Patent No. 77,384, dated April 28, 1868.

IMPROVED FLOOD-GATE.

The Schedule referred to in these Letters Patent and making part of the same.

TO ALL WHOM IT MAY CONCERN:

Be it known that I, H. A. KEPHART, of Fletcher, in the State of Ohio, have invented a new and useful Improvement in Flood-Gates; and I do hereby declare that the following is a full, clear, and exact description of the same, reference being had to the accompanying drawings, and letters of reference marked thereon, making a part of this specification, in which—

Figure 1 is a rear elevation of my invention, and

Figure 2 is a front elevation of the same.

This invention consists of devices for use in a stream of water, for the purpose of preventing valuable property from being carried away thereby, the same operating in such manner as to be always, when in use, at the surface of the stream, at whatever height it may be desired, and removable at pleasure, as will hereinafter fully appear.

To enable those skilled in the art to make and use my invention, I now proceed to describe its construction and operation.

Similar letters in the drawings refer to like parts.

A A represent two vertical wooden posts of suitable size, the same being hinged at their lower ends to the foundation-piers a a, which latter may consist of wooden boxes, sunk to the bottom of the stream, and filled with stones, or they may be mere rocks, in which staples are set, for the attachment of the posts A.

B represents a plank placed horizontally of the posts A, and secured thereto by means of staples, b, in such manner as to slide freely thereon. Vertical slats, c c, &c., are secured to the plank, B, for the purpose of catching anything floating on the surface of the stream, when the water is above the common height. The two slats c, in contact with the posts A, are secured thereto at their tops in any manner that will admit of the adjustment of the plank, B, at heights varying with that of the water.

C represents a second plank, which may be of equal dimensions with the plank, B, and is secured longitudinally thereto by means of hinges, so as to form a valve, its purpose being to supplement in some degree the slats c, by discharging their function in case the water is allowed to fall below the plank, B, and being hinged, to offer no obstruction to the passage of the water in case of a sudden flood.

In addition to the fastenings between the slats c and posts A, I employ a brace, e, attached at one end of the piers a, and at the other end to a transverse bar, h, on the opposite side of the slat c.

The combined strength of all the fastenings, however, should not be so great as to retain the gate in an erect position when a pressure is brought to bear upon it, as from a flood or a mass of drift-wood sufficient to injure it if unyielding. In such a case it is better that the fastenings should break and the gate assume an inclined position, held only by its hinges i i.

By means of these hinges the gate may be laid flat on the bottom of the stream, and held there out of the way of ice during the winter. If preferred, the gate may be removed altogether from the posts A during the winter, and the latter laid on the bottom.

Having thus fully described my invention, what I claim as new, and desire to secure by Letters Patent, is—

The hinged posts A A, in combination with the sliding gate B c, and the valve C, in the manner and for the purpose set forth.

H. A. KEPHART.
